UNITED STATES PATENT OFFICE

156,769

JARDINIERE

George Sakier, Frenchtown, N. J., assignor to Animal Trap Company of America, Lititz, Pa.,
a corporation of Pennsylvania

Application January 2, 1948, Serial No. 143,489

Term of patent 14 years

(Cl. D35—3)

To all whom it may concern:

Be it known that I, George Sakier, a citizen of the United States, residing at Frenchtown, in the county of Hunterdon and State of New Jersey, have invented a new, original, and ornamental Design for a Jardiniere, of which the following is a specification, reference being had to the accompanying drawing, forming part thereof.

In said drawing, the figure is a perspective view of a jardiniere showing my new design. The other side of the jardiniere is similar to the one appearing in the drawing.

I claim:

The ornamental design for a jardiniere, as shown and described.

GEORGE SAKIER.
